(57) **CLAIM**

The ornamental design for an aerosol cap, as shown and described.

DESCRIPTION

FIG. 1 is a perspective view of an aerosol cap in accordance with the present design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings and areas within them depict portion of the aerosol cap that form no part of the claimed design. The broken lines in FIG. 1 depict environmental subject matter and form no part of the claimed design.
